(57) **CLAIM**

I claim the ornamental design for a set of building blocks, as shown and described.

DESCRIPTION

FIG. 1 shows a perspective view of a single block of a set of blocks;

FIG. 2 shows a perspective view of another single block of the set of blocks;

FIG. 3 shows a perspective view of another single block of the set of blocks having an opening on the right-hand side and a cover;

FIG. 4 shows a perspective view of another single block of the set of blocks having an opening on the front side and a cover;
FIG. 5 shows a perspective view of a single block of a set of blocks having an opening on the front side;

FIG. 6 shows a perspective view of another single block of the set of blocks having an opening on the front side;

FIG. 7 shows a perspective view of another single block of the set of blocks having an opening on the front side and a cover;
FIG. 8 shows a perspective view of another single block of the set of blocks;

FIG. 9 shows a front side view of the block shown in FIG. 1;
FIG. 10 shows a front side view of the block shown in FIG. 2;
FIG. 11 shows a front side view of block shown in FIG. 3 with the cover in place;

FIG. 12 shows a front side view of block shown in FIG. 4 without the cover in place;

FIG. 13 shows a front side view of the block shown in FIG. 4 with the cover in place;

FIG. 14 shows a front side view of the block shown in FIG. 5;
FIG. 15 shows a front side view of the block shown in FIG. 6;
FIG. 16 shows a front side view of the block shown in FIG. 7 without the cover in place;

FIG. 17 shows a front side view of the block shown in FIG. 7 with the cover in place;

FIG. 18 shows a front side view of the block shown in FIG. 8;
FIG. 19 shows a bottom side view of the block shown in FIG. 9;

FIG. 20 shows a bottom side view of the block shown in FIG. 10;

FIG. 21 shows a bottom side view of the block shown in FIG. 11;

FIG. 22 shows a bottom side view of the block shown in FIG. 12;

FIG. 23 shows a bottom side view of the block shown in FIG. 13;

FIG. 24 shows a bottom side view of the block shown in FIG. 14;

FIG. 25 shows a bottom side view of the block shown in FIG. 15;

FIG. 26 shows a bottom side view of the block shown in FIG. 16;
FIG. 27 shows a bottom side view of the block shown in FIG. 17;
FIG. 28 shows a bottom side view of the block shown in FIG. 18;
FIG. 29 shows an example of a structure using the blocks of the set shown in FIGS. 1-8;
FIG. 30 shows another example of a structure using the blocks of the set shown in FIGS. 1-8;
FIG. 31 shows another example of a structure using the blocks of the set shown in FIGS. 1-8;
FIG. 32 shows another example of a structure using some of the blocks of the set shown in FIGS. 1-8;
FIG. 33 shows another example of a structure using the blocks of the set shown in FIGS. 1-8;

FIG. 34 shows another example of a structure using some of the blocks of the set shown in FIGS. 1-8;
FIG. 35 shows another example of a structure using some of the blocks of the set shown in FIGS. 1-8;
FIG. 36 shows another example of a structure using some of the blocks of the set shown in FIGS. 1-8;
FIG. 37 shows another example of a structure using the blocks of the set shown in FIGS. 1-8;
FIG. 38 shows another example of a structure using the blocks of the set shown in FIGS. 1-8; and,
FIG. 39 shows another example of a structure using the blocks of the set shown in FIGS. 1-8.
Individual blocks of the set of building blocks are shown separately in FIGS. 1-28 for the ease and clarity of illustration.
